UNITED STATES PATENT OFFICE.

CHARLES F. ROBBINS, OF KEENE, NEW HAMPSHIRE, ASSIGNOR TO MARKEM MACHINE COMPANY, OF BOSTON, MASSACHUSETTS, A CORPORATION OF MASSACHUSETTS.

PRINTING-MACHINE.

1,390,388.

Specification of Letters Patent. Patented Sept. 13, 1921.

Application filed October 8, 1920. Serial No. 415,590.

To all whom it may concern:

Be it known that I, CHARLES F. ROBBINS, a citizen of the United States, residing at Keene, county of Cheshire, State of New Hampshire, have invented an Improvement 5 in Printing-Machines, of which the following description, in connection with the accompanying drawing, is a specification, like characters on the drawing representing like 10 parts.

This invention relates to printing machines of that type having a plurality of platens and a plurality of type-beds arranged about a common center and constructed so that the platens and type-beds 15 may move relative to each other about the common center, thereby bringing each platen into printing relation with the different type-beds successively. A printing machine of 20 this type is illustrated in United States Patent No. 1,279,904, dated September 28, 1918, and I have herein chosen to embody my present invention in a machine having the general construction illustrated in said 25 patent.

One of the objects of the invention is to provide novel means for rotating intermittently the member supporting the platens, and another object of the invention is to 30 provide a novel means for locking said member positively from movement during the printing operation. Other objects of the invention are to improve printing machines of this type, all as will be more fully herein- 35 after set forth.

In order to give an understanding of my invention, I have illustrated in the drawings a selected embodiment thereof which will now be described, after which the novel features 40 will be pointed out in the appended claims.

In the drawings, Figure 1 is a vertical sectional view through a printing machine embodying my invention.

Fig. 2 is a side view of the means for intermittently rotating the platen-supporting member;

Fig. 3 is a vertical sectional view through the frame and plunger showing the manner 50 in which the lock for the platen-supporting member is actuated by the plunger, said view being taken on substantially the line 3—3, Fig. 4;

Fig. 4 is a section on the line 4—4, Fig. 3; 55 1 designates the frame of the printing ma-

chine which is provided at its upper end with a head 2 on which is mounted a plurality of radially arranged type-carrying members 3. These type-carrying members 3 are adapted to have a radial sliding movement in a horizontal direction and are guided in their sliding movement by suitable ways 4. The type-carriers 3 are designed to carry type of any suitable character. These type-carriers are given their radial reciprocating movement in a horizontal direction by means of a plunger 5 which is mounted in the frame 1 centrally thereof for vertical reciprocating movement. Said plunger has a cap 6 at its upper end to which is pivotally connected a plurality of links 7 each of said links being pivoted at 8 to two other links 9 and 10. The links 9 are pivotally connected to the type-carriers 3 and the links 10 are pivotally connected at 11 to the head 70 75 2. With this arrangement the upward movement of the cap 6 will operate through the links to move the type-carriers 3 inwardly toward the center, and downward movement will force the type-carriers outwardly. 80

The lower end of the plunger 5 is connected to the crank portion 12 of a driving shaft 13 by means of a connecting rod 14, and this driving shaft 13 may be driven from any suitable source of power. As here- 85 in shown, it is provided with a gear 15 which may be suitably connected to any driving gear.

Each type carrier has inking rolls 16 associated therewith which are arranged to move 90 downwardly over the type as the type carrier is withdrawn, said rolls in their travel being carried over an inking plate 17.

Rotatably mounted on the frame 1 is a platen-supporting member 18 which carries 95 a plurality of platens 19 that are brought into printing relation with the different type-carriers as the platen-supporting member 18 rotates. This member 18 has an intermittent or step-by-step rotation so that 100 each platen is brought into printing relation with the different type-carriers 3 successively.

The parts thus far described are or may be all as shown in the above-mentioned Patent 105 No. 1,279,904 dated September 28, 1918, and form no part of my present invention.

One feature of the invention relates to the means for rotating the platen-supporting member 18. It is important that the platen- 110

supporting member should be accurately positioned at the end of each forward step in order that the platens may be in the correct position to hold the work properly when the printing head moves against the work to make the printed impression. It is also desirable that the starting and stopping movement of the platen-supporting member should be as easy as possible because of its weight, and that the period during which it is at rest between successive forward movements should be as short as possible and yet permit the printing operation. I have provided herein a simple means for intermittently rotating the platen-supporting member which accomplishes both of these results.

The driving shaft 13 is provided at its end with a crank arm 20 which is connected by a connecting rod 21 to an oscillatory pawl-carrier 22 that is loosely mounted on a stud 23 carried by the frame. 24 indicates a ratchet member in the form of a disk also loosely mounted on the stud 23 and provided in its periphery with a plurality of notches 25. The pawl-carrier 22 has pivotally connected thereto at 26 a spring-pressed feed-pawl 27 which is formed with a tooth or projection 28 adapted to engage in the notches 25. As the shaft 13 rotates, the pawl-carrier is oscillated between the dotted line position shown in Fig. 2 and the full line position, and when it reaches the dotted line position, the spring acting on the pawl will force the tooth 28 into a notch 25, and as it swings into the full line position the disk will be carried with it. The notches 25 have square sides, and the tooth 28 is square so that so long as the tooth is in the notch the pawl-carrier and the disk are rigidly locked together.

Means are provided for disconnecting the lock from the notch 25 when the parts reach the full line position, Fig. 2, and this is herein accomplished by providing the pawl with an extension 29 and by providing the crank arm 20 with an extension 30 which is adapted to engage the end of the pawl at this time. The shaft 13 rotates in the direction of the arrow, Fig. 2, and, therefore, when the parts have reached the position shown in full lines, the portion 30 of the crank arm will engage the end of the pawl and swing the pawl out of engagement with the disk 24. As the crank arm 20 turns from the position shown in Fig. 2, the pawl-carrier will be started from the full to the dotted line position, and as soon as the pawl has been carried beyond the notch 25 with which it has been in engagement and is released from the extension 30, then during further backward movement of the pawl-carrier, said pawl will merely drag over the edge of the disk 24 until said pawl carrier reaches the dotted line position when the pawl will be forced into a notch 25 by the action of the spring. The disk 24

is, therefore, intermittently rotated from the crank shaft 13. This disk 24 has a bevel gear 31 rigid therewith, which bevel gear meshes with a bevel gear 32 on a vertical shaft 33 which is journaled in suitable bearings 34 carried by the frame. The shaft 33 has a pinion 35 thereon which meshes with a ring gear 36 rigid with the platen-supporting member 18. The gears 31, 32, 35, 36 are so timed that each forward step of the gear 31 will rotate the platen-supporting member the distance between one type-carrier and the next succeeding type-carrier, thereby advancing the platens from one to another type-carrier. Inasmuch as the pawl 28 and notches 25 have square faces, the platen-supporting member will be controlled entirely by the pawl-carrier until the pawl is released from the disk, and this does not occur until after the platen-supporting member has been brought to rest. There is, therefore, no danger that the platen-supporting member can overrun.

The arrangement of crank and connecting rod 21 is such that the return of the pawl-carrier from the full to the dotted line position occurs during less than half a rotation of the shaft 13, and, therefore, the forward feeding movement of the platen support occupies more than half a revolution of the shaft 13. This allows the movement to be a relatively easy one, notwithstanding that the machine may be operated at a reasonably rapid speed.

The printed impression is made while the pawl-carrier is returning from its full to the dotted line position, and, therefore, when it has no control over the platen-supporting member. Means are, therefore, provided for locking the platen-supporting member while the printed impression is thus being made, and I have herein provided a novel means which is simple in construction and which is actuated by the plunger 5. The lock is in the form of an annular member 37 which surrounds the plunger 5 and is situated between the top of the platen-supporting member and the head 2. This annular member has a central opening larger than the plunger 5 so that it can move transversely or in a radial direction. It is provided at one end with a guiding arm 38 which operates in a guiding groove 39 in the frame 1, and at the other end is provided with a locking arm 40 which also is guided in a suitable groove in the frame and which is of sufficient length to have locking engagement with one of a plurality of notches 41 formed in the platen-supporting member 18. The annular member 37 is also provided with two inwardly-extending fingers 42 and 43 which are alternately actuated by cams 44 and 45 carried by the plunger. These cams are sustained in grooves 46, 47 extending longitudinally of the plunger and they

are oppositely disposed, as shown best in Fig. 3. In the position shown in Fig. 3 with the plunger down, the finger 42 may be occupying the groove 47 in the plunger, and the finger 43 will be engaged by the cam 45. As the plunger rises and the cam 45 is withdrawn from the finger 43, the cam 44 will begin to act on the finger 42, thereby shifting the locking member to the right, Figs. 3 and 4, and withdrawing the locking arm 40 from a notch 41 of the platen-supporting member 18. When the plunger descends again after the platen-supporting member has been advanced one step forward, the cam 45 acts to throw the locking member to the left, Figs. 3 and 4, into locking engagement with the platen-supporting member. The platen-supporting member is, therefore, unlocked when the plunger is raised and during the time that the platen-supporting member is being rotated, but when the plunger descends and forces the type-carriers outwardly into printing relation with the platen, then the platen-supporting member is locked.

Each platen has associated therewith a work-holding finger 48 which is pivotally mounted on the platen-supporting member at 49 and is acted on by a suitable spring 50 which tends to swing it against the work. Means are provided for moving this work-holding finger into inoperative position at one station in the journey of the platen-supporting member, that is, at the point where the work is removed and unprinted work is put in position. For this purpose an arm 51 is pivotally connected to the head at 52, and one of the pivot pins 8 is extended and has passing transversely therethrough a rod 53, said rod extending loosely through a projection 54 carried by the arm 51. The end of the rod is provided with a collar or nut 55 and a spring 56 which encircles the rod 53 is interposed between the projection 54 and the pivot 8.

When the plunger moves downwardly thereby to force the type-carriers outwardly against the platens, the corresponding downward movement of the pivot 8 acts through the spring 56 to move the arm 51 downwardly, and in such downward movement, this arm engages a projection 57 rigid with the work-holding finger 48. Hence every time that the plunger 5 moves downwardly, the arm 51 is swung downwardly and thereby acts to retract the work-holding finger 48. As the plunger moves upwardly, the spring 50 will return the work-holding finger to its operative position.

While I have illustrated a selected embodiment of my invention, I do not wish to be limited to the constructional features shown.

I claim:

1. In a printing machine of the type having a frame carrying a plurality of ra-

dially-movable type-carriers, a rotatable platen-supporting member carrying a plurality of platens, and means to give the platen-supporting member an intermittent rotative movement, thereby to bring the platens into line with the type-carriers successively, the combination with a plunger reciprocating in the frame for giving the type-carriers their radial movement, of a lock for holding the platen-supporting member from rotation while the printed impression is being made, and means to actuate said lock by the movement of the plunger.

2. In a printing machine of the type having a frame carrying a plurality of radially-movable type-carriers, a rotatable platen-supporting member carrying a plurality of platens, and means to give the platen-supporting member an intermittent rotative movement, thereby to bring the platens into line with the type-carriers successively, the combination with a plunger reciprocating in the frame for giving the type-carriers their radial movement, of a lock for holding the platen-supporting member from rotation while the printed impression is being made, and means to move the lock into locking position by movement of the plunger in one direction and to release the lock by movement of the plunger in the other direction.

3. In a printing machine of the type having a frame carrying a plurality of radially-movable type-carriers, a rotatable platen-supporting member carrying a plurality of platens, and means to give the platen-supporting member an intermittent rotative movement, thereby to bring the platens into line with the type-carriers successively, the combination with a plunger reciprocating in the frame for giving the type-carriers their radial movement, of a lock for holding the platen-supporting member from rotation while the printed impression is being made, and a cam on the plunger to move the lock into locking position.

4. In a printing machine of the type having a frame carrying a plurality of radially-movable type-carriers, a rotatable platen-supporting member carrying a plurality of platens, and means to give the platen-supporting member an intermittent rotative movement, thereby to bring the platens into line with the type-carriers successively, the combination with a plunger reciprocating in the frame for giving the type-carriers their radial movement, of a lock for holding the platen-supporting member from rotation while the printed impression is being made, a cam on the plunger to move the lock into locking position, and another cam to release the lock.

5. In a printing machine of the type having a plurality of type-carriers, and a corresponding number of platens arranged

about a common center, a rotary platen-supporting member sustaining the platens, and means including a crank shaft for moving the type-carriers radially toward and from the platens, the combination with said platen-supporting member, of a crank arm on said crank shaft, an oscillatory pawl-carrier connected to said crank arm, a rotary notched disk, a pawl pivotally connected to said carrier and coöperating with said disk to rotate the latter intermittently as the pawl-carrier is oscillating, a bevel gear rigid with said notched disk, and gearing connecting said bevel-gear to the platen-supporting member.

6. In a printing machine of the type having a plurality of type-carriers, and a corresponding number of platens arranged about a common center, a rotary platen-supporting member sustaining the platens, and means including a crank shaft for moving the type-carriers radially toward and from the platens, the combination with said platen-supporting member, of a crank arm on said crank shaft, an oscillatory pawl-carrier connected to said crank arm, a rotary notched disk, a pawl pivotally connected to said carrier and coöperating with said disk to rotate the latter intermittently as the pawl-carrier is oscillating, a bevel gear rigid with said notched disk, gearing connecting said bevel-gear to the platen-supporting member, and an extension on the crank arm constructed to engage the pawl and periodically release it from the disk.

7. In a printing machine of the class described, the combination with a frame carrying type-carriers, of a rotatable platen-supporting member, platens supported thereby,

means including a crank shaft for moving the type-carriers toward and from the platens, a notched disk mounted to rotate about an axis parallel to the crank shaft, an oscillatory pawl-carrier situated co-axially with said disk, a spring-pressed pawl mounted on said carrier, a connection between said pawl-carrier and crank shaft whereby the latter is oscillated, and gearing connecting the notched disk with the platen-supporting member.

8. In a printing machine of the class described, the combination with a frame carrying type carriers, of a rotatable platen-supporting member carrying a platen, means to rotate the platen-supporting member intermittently to bring the platen into operative position relative to the type carriers successively, means to move each type carrier toward and from said platen when the latter is in such operative position, a work-holding finger associated with said platen for holding work thereagainst, and means actuated by the movement of each type carrier toward the platen to move said finger into inoperative position.

9. In a printing machine of the class described, the combination with a frame carrying type-carriers, of a rotatable platen-supporting member carrying a platen, means to move the type-carriers toward and from the platen, spring-pressed work holding fingers for holding the work against the platen, and means actuated by the movement of the type-carriers toward the platen to move the fingers into inoperative position.

In testimony whereof, I have signed my name to this specification.

CHARLES F. ROBBINS.
